SHIPPING CARRIER FOR ROLLS

Edwin O. Carlson, Chicago, Ill., assignor to Copy
Papers, Inc., Chicago, Ill., a corporation of
Illinois

Application June 21, 1935, Serial No. 27,657

1 Claim. (Cl. 206—59)

This invention relates to a shipping carrier for rolls and more particularly to a shipping carrier for gelatin duplicating rolls.

It has heretofore been customary to use metal, 5 or wood carriers for gelatin duplicating rolls. This practice, however, is relatively expensive, since the carriers are not generally reused but are thrown away.

It is therefore an important object of this invention to provide a relatively inexpensive shipping carrier for gelatin duplicating rolls and the like, wherein the carrier is a tube or core made from fibrous material, such as chip board, straw board, mechanical wood pulp or the like.

15 It is a further important object of this invention to provide a shipping carrier for gelatin duplicating rolls and the like that can be used at little expense in the shipping of the rolls and that is of such dimensions as to fit over the usual 20 sizes of spindles employed on duplicating machines.

Other and further important objects of this invention will be apparent from the disclosures in the specification and the accompanying drawings.

25 This invention (in a preferred form) is illustrated in the drawing and hereinafter more fully described.

On the drawing:

30 Figure 1 is a side elevational view of a shipping carrier for gelatin duplicating rolls with the roll wound thereon.

Figure 2 is an end elevational view of the same.

35 Figure 3 is a fragmentary enlarged view showing the leader strip of the gelatin roll and a shipping carrier of my invention, preparatory to winding the gelatin strip thereon.

40 Figure 4 is a sectional view of the shipping carrier mounted on a spindle with the gelatin roll being unwound.

Figure 5 is a fragmentary enlarged sectional view of the end of the leader strip.

45 As shown on the drawing:

The reference numeral 10 designates generally a shipping carrier for gelatin duplicating rolls or the like embodying the principles of my invention. As shown in Figs. 1 and 2, a roll 11 of gelatin coated strip material 12 is wound up on the shipping carrier 10 for storage and transportation purposes.

50 The gelatin strip material 12 is provided with a leader strip 13 of cloth, fiber backing stock, or the like that is secured to the end of the gelatin strip by stitching or by means of adhesive, as indicated at 14, or that is a continuous and integral part of the backing material used as a base for mounting the gelatin of the roll 55 itself. The end of the leader strip 13 is reduced

to form a tapered portion 15, the leading end of which is suitably reinforced, as by a metal strip 16. One manner of engaging the end edge by the metal strip 16 is illustrated in Fig. 5, wherein the metal strip 16 and end edge 17 are folded about themselves and flattened somewhat together. The reinforced end 18 thus formed is of increased thickness beyond that of the leader strip itself.

The shipping carrier 10 comprises a core or tube preferably formed of cheap fibrous material, such as paper board, straw board, or the like. In dimensions, the core 10 is slightly longer than the width of the gelatin strip 12 so that its ends project beyond the roll 11 as indicated at 19. The inside diameter of the carrier 10 is not less than 1 1/4 inches, so that it may be slipped over any of the customary sizes of spindles used in rewinding the gelatin roll. The thickness of the wall of the carrier tube or core 20 10 is preferably between the limits of $\frac{1}{16}$ inch and $\frac{3}{8}$ inch, so as to provide the necessary strength and at the same time be comparatively light.

A slot 20 is provided in the carrier 10 for receiving the reinforced end 18 of the leader strip. Said slot 10 extends longitudinally of the tube or core and its ends are spaced equally from the ends of said core. The length of the slot 20 is substantially the same as the width of the reinforced end 16 and the width of the slot 20 is substantially the same as the thickness of the reinforced end 18. Thus, when the reinforced end 18 is inserted into the slot 20, it fits snugly therein and is held frictionally against removal. It should be noted that the thickness of the wall of the core 10 is such that the reinforced end 18 may be inserted into the slot and substantially fill the same without projecting into the interior of the core and without forming any projection beyond the outer surface of the core. The reinforced end 18 therefore does not interfere with the insertion of a spindle 21 within the core, as is necessary in rewinding the gelatin strip material from the roll 11 onto a permanent spindle 45 for use in a duplicating machine.

In starting the winding of the gelatin strip material onto a shipping carrier of my invention, the reinforced end 18 is inserted into the slot 20, thereby centering the strip material with respect to the ends of the carrier. The leader strip 13 is then wrapped around the core 10 and the winding of the gelatin strip material continued to form the roll 11.

55 It will be appreciated that the length of the carrier 10 may be varied to suit different widths of gelatin rolls, but it is preferable to provide the same length of slot 20 regardless of the overall length of the carrier. Accordingly, the length 60

of the reinforced end 18 also remains the same, regardless of the width of the gelatin roll, so that the reinforced end may always be properly fitted into and retained in the slot 20 of any 5 particular carrier.

I am aware that many changes may be made and numerous details of construction may be varied through a wide range without departing from the principles of this invention, and I, 10 therefore, do not purpose limiting the patent granted hereon otherwise than necessitated by the prior art.

I claim as my invention:

In a duplicator roll assembly in which an elongated tube frictionally engages a smooth spindle 15

but is slidable thereon because of the absence of protuberances on the inner face of the tube, an elongated tube of fibrous material, such as paper board, provided with a longitudinally extending slot in the wall thereof and disposed intermediate the ends thereof, an anchor member of substantially the thickness of the wall of said tube laid in said slot, and a roll of gelatin having a leader strip secured to said anchor member, said tube providing a core on which a roll of gelatin 10 is anchored and wound, and providing with said gelatin roll and its anchor an assembly readily slideable over a smooth spindle for use in a duplicator.

EDWIN O. CARLSON. 15
